UNITED STATES PATENT OFFICE.

CLINTON E. WOODS, OF CHICAGO, ILLINOIS.

DESIGN FOR A FRAME FOR DYNAMO-MACHINES.

SPECIFICATION forming part of Design No. 25,032, dated December 31, 1895.

Application filed June 11, 1894. Serial No. 514,252. Term of patent 14 years.

To all whom it may concern:

Be it known that I, CLINTON E. Woods, a citizen of the United States, residing at Chicago, county of Cook, and State of Illinois, have invented and produced a new and original Design for Frames for Dynamo-Electric Machines, of which the following is a specification.

My invention relates to the form or design of a frame for dynamo-electric machines, and is illustrated in the accompanying drawings, wherein—

Figure 1 is a side view of a frame embodying my invention. Fig. 2 is a perspective view of the same.

Like letters refer to like parts throughout the several figures.

A is the sub-base of the frame substantially round or slightly elliptical. B is the base-ring superimposed on the sub-base and having the standards C C and the upwardly-projecting foot or step D adapted to receive the laterally-projecting lug E on the corrugated or indented magnet-ring. The standards C

C are curved on their sides, as indicated. 25 Supported upon the steps D is an annular portion or ring consisting of the comparatively straight portions F F and the intermediate portions G G, said intermediate portions being indented or scalloped on the outside and projecting toward the center of the ring on the inside, as shown.

The essential feature of my design therefore embraces the substantially round or elliptical base with the curved standards thereon 35 and the annular portion or ring provided with the indentations or scallops and having the upwardly-projecting pieces extending toward the center of the ring.

What I claim as my invention is— 40

The design for the frame of a dynamo electric machine, substantially as herein shown and described.

CLINTON E. WOODS.
